ADAPTER FOR MOUNTING LIMBS ON ARTIFICIAL TREES

Terry Hermanson, New York, N.Y., assignor to
Mr. Christmas Incorporated, New York, N.Y.

Filed Apr. 6, 1971, Ser. No. 131,851

Term of patent 14 years

Int. Cl. D8—08

U.S. Cl. D8—255

FIG. 1

FIG. 2

FIG. 3

FIG. 4

FIG. 1 is a perspective view of an adapter for mounting limbs on artificial trees constituting my new design;

FIG. 2 is an end view of the device shown in FIG. 1;

FIG. 3 is a side view of the device shown in FIG. 1; and

FIG. 4 is a top plan view of the device shown in FIG. 1. I claim:

The ornamental design for an adapter for mounting limbs on artificial trees, as shown.
